Primary Examiner — Elizabeth Albert(74) *Attorney, Agent, or Firm* — QuickPatents; Kevin Prince(57) **CLAIM**

I claim the ornamental design for an ergonomic implement holder, as shown and described.

DESCRIPTION

FIG. 1 is a perspective view of an ergonomic implement holder, showing my new design;

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines showing a hand in FIG. 1 and the rear end of the ergonomic implement holder in FIGS. 1-7 are included for the purpose of showing environmental matter that forms no part of the claimed design.
